(57) **CLAIM**

The ornamental design for a lid for a storage container, substantially as shown and described.

DESCRIPTION

FIG. 1 is a perspective view of the “lid for a storage container”, showing my new design;

FIG. 2 is a right side elevation view thereof;

FIG. 3 is a left side elevation view thereof;

FIG. 4 is a front side elevation view thereof;

FIG. 5 is a back side elevation view thereof;

FIG. 6 is a top plan view thereof;

FIG. 7 is a bottom plan view thereof;

FIG. 8 is a perspective view of a second embodiment of the “lid for a storage container”, showing my new design;

FIG. 9 is a right side elevation view thereof;

FIG. 10 is a left side elevation view thereof;

FIG. 11 is a front side elevation view thereof;

FIG. 12 is a back side elevation view thereof;

FIG. 13 is a top plan view thereof;

FIG. 14 is a bottom plan view thereof;

FIG. 15 is a perspective view of a third embodiment of the “lid for a storage container”, showing my new design;

FIG. 16 is a right side elevation view thereof;

FIG. 17 is a left side elevation view thereof;

FIG. 18 is a front side elevation view thereof;

FIG. 19 is a back side elevation view thereof;

FIG. 20 is a top plan view thereof; and,

FIG. 21 is a bottom plan view thereof.

Color is not a claimed feature of the design.

The broken lines in the drawings represent unclaimed portions of the design.

1 Claim, 15 Drawing Sheets
